JONATHAN PETERSON, OF BROOKLYN, NEW YORK, ASSIGNOR TO COMBINATION MACHINE COMPANY, OF NEW YORK, N. Y., A CORPORATION OF DELAWARE.

PIPE CLEANER.

Application filed November 24, 1925. Serial No. 71,044.

This invention relates to pipe cleaners of the general class represented by a long twisted wire body, which carries a multiplicity of fibers forming a flexible brush surface for 5 cleaning the bores of pipe stems.

The general object of the invention is to arrange or provide a pipe cleaner of this general class in the form of a flat coil, for greater convenience and other advantages in 10 carrying and use.

Pipe cleaners such as above described have heretofore been provided in two forms:— Either straight, or bent—“doubled” in the middle. In order to go through the stem bore of the average pipe the cleaners have to be of considerable length and are in fact usually about $7\frac{1}{2}$ ” long. Therefore when they are furnished in packages in straight form the package is of such length that it 15 is not readily accommodated in the average pocket. The containers are also necessarily very flexible or bendable in order to easily follow the contour of the stem bore, and therefore these straight cleaners when carried in the pocket are frequently bent to such an extent that it is difficult to straighten them for proper insertion in the pipe stem. This causes great annoyance to pipe smokers and relatively great waste of the cleaners.

When furnished in “doubled” form the single cleaner or a package of them is, of course, much shorter, but the central bend in the wire body must be made quite sharp to provide the desired compactness, and it is 20 difficult or impossible to properly straighten out this bend, and the cleaner tends to easily re-bend or kink at the place where it was originally bent, and it is difficult or impossible to properly pass this bent or kinked portion 25 through the pipe stem.

To avoid these difficulties and disadvantages, and at the same time to provide an appliance which is in much more compact form than any heretofore provided, and capable of being easily carried in any pocket 30 without inconvenience to the user or risk of damage to the cleaner, or more conveniently and compactly packaged, as explained hereafter, I arrange or provide a cleaner which 35 may have the basic characteristics of the ordinary pipe cleaner as above described, that is a bendable wire body provided with a brush 40 surface in the form of a flat, close coil or

convolute, which may be circular or oval in general form or may even be of more or less 55 polygonal outline. The inherent characteristics of the bendable wire body are such that it is self-retained in the stated coil form, without any tendency to spring out of shape or uncoil until intentionally uncoiled by the 60 user; and no container or retainer is needed to maintain the cleaner in the stated form.

The cleaner so arranged is very compact, thin and flat and has a diameter of only 65 about 1” or less, and therefore may be easily and conveniently carried in any pocket, such as a vest or ticket pocket, without interfering with other pocket contents and with no practical possibility of deformation or other injury to the cleaner. The curvature of the wire body is moderate and regular, without any sharp bending or kinking 70 of the wire at any point, and it may therefore be easily uncoiled or approximately or entirely straightened for use, or fed into the 75 pipe stem bore and at the same time automatically uncoiled, as more particularly explained hereafter, without any risk or practical possibility of producing any undesired kinks or sharp bends.

80 The accompanying drawing shows certain exemplifying embodiments of the invention. After considering this example skilled persons will understand that many variations may be made without departing from the 85 principles of the invention, and I contemplate the employment of any structures that are properly within the scope of the appended claims.

Fig. 1 is a plan view of a pipe cleaner embodying the invention in one form.

Fig. 1^a is an edge view.

Fig. 2 is a plan view of a modification.

Fig. 3 illustrates one convenient mode of use.

Fig. 4 indicates one manner of convenient pocket carrying of one typical form of the cleaner.

Fig. 5 shows one convenient way in which the cleaners may be packaged.

Fig. 6 explains the fundamental structure and shape of one ordinary form of pipe cleaner, as heretofore made and sold.

Fig. 7 shows the same type of pipe cleaner in the other common commercial form, 105 that is, bent at the center, or “doubled.”

The typical commercial pipe cleaner is shown in one of the usual forms, that is, straight, in Fig. 6. The base or body 1 consists of two bendable wires tightly twisted together and holding between them fibers or bristles 2, which are by the twisting of the wire placed in a generally helical arrangement, so that the entire surface of the finished cleaner is a substantially cylindrical, flexible brush. The wire body is here referred to as "bendable" in substantial distinction from merely "flexible," because the wire is of such quality or temper that it is easily bent and tends to remain in any form produced by such bending. When sharply bent at any place, however, it is difficult or impossible to again entirely straighten out this bend, and of course, the metal is so deformed by sharp bending that it is substantially weakened and tends to easily bend or kink again at the same point. The commercial cleaner in straight form as shown in Fig. 6, is substantially $7\frac{1}{2}$ " long and is usually sold in packages of about a dozen. Where the user pockets them in package form or singly, the length of the cleaners is such that they will protrude more or less from the average pocket, and even if entirely contained within a pocket they are so long that they are practically always bent or kinked to a substantial extent by reason of natural body movements and bending of the pocket of the garment. The long straight cleaner moreover, is inconvenient for carrying because of its length, regardless of bending, and is usually packaged with a long paper wrapper about the central part of the package and the ends of the cleaners protruding so that these ends become bent over more or less sharply at the point where they protrude from the wrapper, producing very often the sharp bends or kinks above referred to.

Fig. 7 shows another common commercial form, in which the same cleaner is bent in the middle or "doubled," and this bend is substantially sharp and cannot be readily straightened out, for reasons above explained. While a package of the doubled cleaners is shorter lengthwise than when the cleaners are straight, it is much more bulky laterally and therefore inconvenient to carry, and the cleaners are also liable to more or less additional deformation in the ways above described, because the doubled package is still about $3\frac{3}{4}$ " long. When the pipe smoker attempts to use one of the cleaners of either commercial form, he finds that it is, as a rule, more or less bent or kinked and especially in the case of the doubled cleaners there is always a sharp bend at the middle, which cannot be readily straightened out, and in either case when the cleaner is inserted into the pipe stem bore, additional undesired bending occurs with obvious in-

convenience to the user, and many defective cleaners have to be thrown away.

By experiment and discovery I have found that the above difficulties and disadvantages may be entirely avoided and convenient pocket carrying at the same time provided for, by arranging one of the above described or any substantially similar or suitable pipe cleaner in the form of a substantially flat coil or convolute, the turns of which are usually close together and the plane dimensions are usually as small as is practicable for the total length of the cleaner, or in other words, the coil is preferably substantially close and compact.

Fig. 1 shows the cleaner A in the form of a flat circular coil or convolute, the turns of which lie close together as above stated, and the central turn or coil a is of substantially the smallest practicable radius in order to provide for the smallest practical overall dimension or diameter.

Fig. 2 shows another arrangement in which the coil or convolute is substantially oval. Evidently the exact form may vary considerably and the general shape of the coils or convolutes may even be substantially polygonal. In such cases they will, of course, approach in a geometrical sense the oval or circular formation of Fig. 1 or 2.

Fig. 3 shows how the outward end of the coiled cleaner may be easily inserted in the end of a pipe stem and evidently, as this portion of the cleaner is pushed farther and farther into the stem, the coil is automatically unrolled and straightened, or the curvature is modified, to practically automatically and easily conform to the shape of the stem bore. There is no sharp bend or kink and no possibility of rebending or kinking at such a point. There is also a minimum of waste from defective cleaners. Much greater facility in use is thus provided as compared with previous forms, but particularly the thin, compact arrangement of the cleaner, as shown in edge view, Fig. 1^a, permits it to be easily and conveniently carried in any pocket, such as vest pocket V, Fig. 4. When so carried it takes up no appreciable room, causes no inconvenience or discomfort to the user, and is practically immune from damage since any bending of the user's body or the garment pocket is insufficient to appreciably deform or permanently distort the cleaner, and it will remain in proper condition for use indefinitely. There is therefore no risk of inadvertent bending or kinking as above explained in connection with the ordinary straight or doubled cleaners, and waste is evidently immensely reduced.

Fig. 5 shows how any reasonable number, say a dozen or more of the cleaners, may be very compactly packaged in roll form and when so packaged, the roll takes up very

little space in the pocket or elsewhere, and the cleaners are practically immune from injury, for obvious reasons.

I claim:—

- 5 1. As a new article of manufacture, a pipe cleaner in the form of a flat coil which is self-retained in stated form by its inherent characteristics.
- 10 2. As a new article of manufacture, a pipe cleaner in the form of an extensible, flat convolute, self-retained in the stated form by the inherent bendable character of the pipe cleaner.
- 15 3. As a new article of manufacture, a pipe cleaner in the form of an extensible, circular coil, the convolutions of which are all in substantially the same plane, and which is self-retained in the stated form by the inherent bendable character of the pipe cleaner.
- 20 4. A pipe cleaner consisting of a bendable wire body of substantial length provided

with a brush surface substantially throughout its length and coiled in the form of an extensible compact, flat convolute, this form being retained until altered for use by the natural set of the wire body.

5. A pipe cleaner consisting of a bendable wire body of substantial length provided with a brush surface substantially throughout its length and coiled in the form of an extensible compact, flat, round coil, this form being retained until altered for use by the natural set of the wire body.

6. A pipe cleaner consisting of a substantially non-resilient, bendable wire body of substantial length, provided with a brush surface self-retained in the form of a close, substantially round coil, the convolutions of which lie substantially in the same plane.

Signed at New York city in the county of New York and State of New York this 23rd day of Novbr. A. D. 1925.

JONATHAN PETERSON.
